POST TOP OUTDOOR LUMINAIRE

Frank Van Steenhoven, Newark, Ohio, assignor to Holophane Company, Inc., New York, N.Y., a corporation of Delaware

Filed Sept. 16, 1963, Ser. No. 76,598

Term of patent 14 years

(Cl. D48—31)

7191.

T19-2-

FIG. 1 is a perspective view of a post top outdoor luminaire showing my new design;

FIG. 2 is a side elevational view thereof;

FIG. 3 is a top plan view thereof; and

FIG. 4 is a bottom plan view thereof.

The fragmentary post shown in broken lines in FIGS. 1 and 2 is for illustrative purposes only.

I claim:

The ornamental design for a post top outdoor luminaire, substantially as shown and described.
